C. T. MILLER

VENTILATOR

Filed March 31, 1927

Inventor

Charles J. Miller

Lynn A. Latta Attorney

UNITED STATES PATENT OFFICE.

CHARLES T. MILLER, OF SIOUX CITY, IOWA.

VENTILATOR.

Application filed March 31, 1927. Serial No. 179,882.

My invention relates to ventilators and cupolas and has for its object to provide a ventilator of a very much cheaper construction than any heretofore devised.

5 A further object of the invention is to provide a ventilator having such cheapness of construction which is also of simple and durable construction.

The invention is carried out generally by 10 doing away with all brackets ordinarily used in connecting the hood of the ventilator to the base and forming the hood and bracket integrally of a single square sheet of metal whereby there is no waste whatever in forming 15 the hood.

A further object is to provide a construction of extreme rigidity that a much lighter metal may be used, than is ordinarily found necessary in ventilators.

20 Another object of the invention is to provide a ventilator which may be composed of a plurality of superimposed hoods which may be readily disassembled and nested together for shipping purposes.

25 A further object of the invention is to provide a ventilator giving a maximum exhaust arrangement for any direction of wind travel.

With these and other objects in view, my invention consists in the construction, arrangement and combination of the various parts of my device, whereby the objects contemplated are attained, as hereinafter more fully set forth, pointed out in my claim, and illustrated in the accompanying drawings, 35 in which:

Fig. 1 is a side elevation of one form of my invention.

Fig. 2 is an inverted plan view of the same.

40 Fig. 3 is a perspective view of another form of the invention.

Fig. 4 is a vertical, sectional view of the same, taken on the line 4-4 of Fig. 3.

Fig. 5 is a view of the blank used in making the base.

Fig. 6 shows the blank for the hood, and

Fig. 7 shows the blank for an intermediate hood.

In carrying out my invention, a base A 50 is formed of a single oblong sheet of metal 10, shown in Fig. 5, of length substantially three and one-half times its width, so that, when curved to form the base A, the diameter of the base will be substantially the same as its height. The ends are riveted or bolted together, as at 11.

The hood B is formed of a single square sheet of metal, shown in Fig. 5, and since the sheet is square, it may be cut without leaving any scrap of material. The hoods 60 B and C, in the form of invention shown in Figs. 3 and 4, are formed in identical manner to the hood B of the other form of the device, with the exception of a circular opening 13, in the hood C. 65

The blank for the hood C is shown in Fig. 7. Each hood is formed by bending along two pairs of lines 14 parallel to the respective side edges of the blank 12 and equidistant from those edges. The side 70 edges of the blank 12 are thus divided into the outer edge portions 15 and central edge portions 16 and the lines of bending divide themselves by crossing each other into the outer portions 17 and the inner portions 18. 75 These same numbers will be used in referring to the bends or corners produced in the metal of the finished hood.

It may now be noted that the corners of the blank are collapsed inwardly between 80 the line portions 17 at each corner of the blank, thereby forming a bend 19 in the opposite direction to the bends 17 and forming the triangular areas 20.

The metal adjacent the bend 19 is to serve 85 as a bracket for securing the hood to the base A and to this end the bends 19 are brought inwardly to positions perpendicular to the original plane of the sheet 12, which plane is retained in the central square 90 21 formed between the bends 18. This brings the bends 19 to parallel positions, equidistantly spaced from each other in all directions so that each may lie in contact with the cylindrical surface of the base A. 95

In determining the proper spacing of the lines 14 of each pair, the distance is computed as the square root of twice the square of the external radius of the base A, that is,

$$(16) = \sqrt{2}(\text{radius A})^2.$$

100 Thus there will be formed a hood, having the triangular side walls 20, the sloping square walls 22 and the top wall 21. The hood is secured to the base A by means of stone bolts 23, extended through the bends 19 and through the wall of the base. A very rigid construction is thereby secured, the entire walls 20 serving as brackets formed integrally with the inclined walls 22 and the 110 upper walls 21. The metal used in the construction of a hood, according to my invention,

tion, may be made much lighter than the metal used in constructing the ordinary hood of equal size and capacity. The bracket portions of the hood serve to stiffen the base 5 against collapsing, rather than the base serving to position the brackets, as in the ordinary ventilator.

The slope of the walls 22 will be 45° , since the bends 17 and the edges 15 are necessarily 10 of equal length, no matter what the spacing between the lines 14 will be, and thereby form, together with the bends 19, right angle triangles of which the bends 19 are the hypotenuses. Consequently, a ventilator 15 may be made with either one or several hoods, the same exhaust capacity obtained by spacing the single hood higher above the base than the spacing between the double hoods of Figs. 3 and 4 and the increased 20 height may be taken care of by using a larger blank of material and spacing the lines 14 closer together in proportion to the dimensions of the blank, thereby increasing the length of the bends 19 in proportion to 25 the width of the walls 22, the slope of the walls in any case being 45° .

Thus, in figuring the dimensions of the ventilator hood, the distance between the lines 14 will be determined, as hereinbefore 30 described, by reference to the diameter of the base A and the length of the lines 19 will be determined by the height to which the hood is to be raised above the base, which in turn will be determined by the 35 diameter of the base and the number of hood sections employed. In the single hood ventilator, shown in Fig. 1, the distance from the upper walls 21 to the upper edge of the base A is made approximately 40 the same as the diameter of the base, whereas, in the double type ventilator, the distance from the upper hood to the upper edge of the base is the same as in the single hood type and the distance from the upper 45 points of the intermediate hood C to the upper edge of the base is one-half of this amount. It has been found that the exhaust area of the ventilator thus obtained will be approximately twice the area of the base. 50 The exhaust arrangement thus referred to is the sum of all the open areas between the walls of the hood and the upper edge of the base. If a wind is blowing transversely to the axis of the ventilator and in 55 the direction of two opposed ports of the hood, the ventilator will exhaust from three of the ports. If a wind is blowing at an angle of 45° to the direction just mentioned and transversely of the axis of the 60 ventilator, it will enter two of the ports and leave the other two. In this case, the actual exhaust area will be one-half the potential area or the same as the area of the base.

65 If a wind is blowing downwardly, there

will be a suction produced, tending to draw the air from all of the ports. It will be noted in the form shown in Fig. 3 that the upper hood is secured to the lower hood by bolts 23^a. By removing the bolts 23 and 23^a, 70 the hoods in either type may be nested together around the base so as to occupy substantially half of the original volume of the ventilator.

The advantage of using the intermediate 75 hood C lies partly in strength and partly in the aided protection against downwardly directed currents. The advantage of the type of construction employed, lies in the cheapness, the simplicity in assembling, the 80 extreme rigidity, and the lack of waste material. A further advantage lies in the fact that the hood may be produced without a special die by first bending the blank upon the lines 14, then straightening it and bending it completely from the corner to corner, to form the lines 19, then again bringing it approximately to its original plane, the creases remaining, however, sufficiently to allow the ready formation of the hood by 85 inward pressure against the portions 20 in the proper direction. Thus ventilators may be built to order without the use of special machinery and without any great 90 expense in time of the workman, since the 95 operation in every case is the same and the computing of dimensions is reduced to a very simple formula, the elements of which vary only slightly for various ratios between the height and width of the completed hood. 100 The construction shown in Fig. 1 will be employed chiefly for chimney tops while the construction shown in Fig. 3 is more adaptable as a larger ventilator for buildings 105 and the like. I have found that the ventilator may be produced at substantially one-half the cost of the cheapest ventilator now on the market. Only twelve bolts are required in the form shown in Fig. 3, and 110 eight or possibly four, in the form shown in Fig. 1. Only three sheets of material need be employed for the form shown in Fig. 3.

Due to the absence of brackets, there is no opportunity for a bird to build a nest within the ventilator and the inclined walls make 115 it difficult for a bird to find lodging upon the ventilator. The wind from any direction will only increase the draft of the ventilator.

Some changes may be made in the construction and arrangement of the parts of 120 my invention without departing from the real spirit and purpose of my invention, and it is my intention to cover by my claim, any modified forms of structure or use of 125 mechanical equivalents, which may be reasonably included within its scope.

I claim as my invention:

A ventilator comprising a cylindrical, tubular base and a one-piece hood, formed of 130 a square sheet of material, bent upon crossed

pairs of lines parallel to the respective side edges of the blank and diagonal lines joining the corners of the blank with the crossing points of said first mentioned lines, the 5 bends of said diagonal lines being collapsed inwardly to positions perpendicular to the original plane of the blank and parallel to

each other and fastening elements secured through said last mentioned bends and the wall of the base.

Signed this 28th day of March, 1927, at Sioux City, in the county of Woodbury and State of Iowa.

CHARLES T. MILLER.
